(57) **CLAIM**

The ornamental design for a “tool for applying a chalk line”, as shown and described.

DESCRIPTION

FIG. 1 is a top, right side and rear perspective view of a tool for applying a chalk line according to my design;
FIG. 2 is a top plan view thereof;
FIG. 3 is a right side elevational view thereof;
FIG. 4 is a left side elevational view thereof;
FIG. 5 is a bottom plan view thereof;
FIG. 6 is a rear elevational view thereof;
FIG. 7 is a front elevational view thereof; and,
FIG. 8 is a perspective view similar to FIG. 1 illustrating the tool handle in an operating condition.
